UNITED STATES PATENT OFFICE.

HARRY W. CRANE, OF PHILADELPHIA, PENNSYLVANIA.

DETACHABLE AND INTERCHANGEABLE HEEL.

1,115,054.

Specification of Letters Patent. Patented Oct. 27, 1914.

Application filed January 27, 1914. Serial No. 314,822.

To all whom it may concern:

Be it known that I, HARRY W. CRANE, a citizen of the United States, residing at Philadelphia, in the county of Philadelphia and State of Pennsylvania, have invented new and useful Improvements in Detachable and Interchangeable Heels, of which the following is a specification.

My invention relates to new and useful improvements in detachable and interchangeable heels, and has for its object to provide an exceedingly simple and effective device of this character, which may be readily and quickly attached to or detached from the ordinary leather heel of a shoe.

A further object of the invention is to provide a clamp which may be readily secured to the ordinary leather heel of a shoe adapted to co-act with a locking plate carried by the detachable heel, whereby the latter may be securely held in place without the likelihood of it becoming accidentally detached.

With these ends in view this invention consists in the details of construction and combination of elements hereinafter set forth and then specifically designated by the claims.

In order that those skilled in the art to which this invention appertains may understand how to make and use the same, I will describe its construction in detail, referring by numeral to the accompanying drawing forming a part of this specification, in which—

Figure 1 is a central longitudinal section of my improved heel showing the same attached to a shoe. Fig. 2, is a section at the line 2—2 of Fig. 1. Fig. 3, is an inverted plan view of the clamp. Fig. 4, is a side elevation thereof. Fig. 5, is an end view thereof. Fig. 6, is a plan view of the locking plate. Fig. 7, is a side elevation thereof; and Fig. 8, is an end view thereof.

In carrying out my invention as here embodied 2 represents the upper of an ordinary shoe, 3 the sole and 4 the heel.

5 denotes the clamp comprising a cupped up body portion 6 composed of the roof 7 and side walls 8 from which projects the flange 9 at right angles to said side walls 8. From the roof 7 at the front end thereof projects the extension 10 at right angles to the roof, forming the front wall of the body 55 in which is formed the opening 11.

Projecting downward from the roof of

the clamp is a partition 12 in which formed the arms 13, the metal intermediate said arms being bent back toward the roof to form the angular guide and rest 14. The partition 12 from which the arms and guide or rests are formed is cut and stamped from the roof of the body as plainly shown in Fig. 3; and said roof also has a number of perforations 15 therein through which pass the attaching nails 16 or their equivalent for fastening the clamp to the leather heel of the ordinary shoe.

17 is the locking plate having a pair of parallel slits 18 formed therein projecting longitudinally from the front edge, thereby forming a tongue 19 which is bent arcuate in shape to form a bowed spring having a pair of opposite slits 20 formed therein, one of which projects from each edge of the tongue formed by the slits 18.

In producing the tongue from the locking plate 17, a pair of arms 21 are formed and these with the edge of the balance of the body of the locking plate form a flange 22 similar to the flange 9 of the clamp. From the locking plate are also formed a number of prongs 22 which assist in holding said locking plate to the detachable heel 23 here shown as being made of rubber and provided in its upper face with a cavity or socket 24 open at the front end and provided at the base of said cavity with a radiating recess 25 into which extend the edge of the locking plate when the same is placed in the cavity 24, and when the detachable heel is formed of rubber, said locking plate is vulcanized thereto by means of the prongs 22. When the clamp is secured to the leather heel of an ordinary shoe, it will be understood that a detachable heel constructed as herein described may be readily attached to the shoe by bringing the flange 9 of the clamp and registration with the recess 25 and then sliding the detachable heel 23 into the position shown in Fig. 1, and it will be understood that as the detachable heel is moved along the bowed spring tongue 19 will contact with the arms 13 and be forced toward the body of the detachable heel until the slots 20 in the bowed spring tongue come into alinement with said arms 13, after which said tongue 19 will return to its normal position, thereby locking the detachable heel upon the shoe.

To remove the detachable heel from the shoe it will be necessary to disengage the

bowed spring tongue 19 from the arms 13 and be momentarily disengaged until the detachable heel can be drawn rearwardly sufficiently to bring the slots 20 out of alignment with the arms 13 at which time the detachable heel may be entirely separated from the shoe. To accomplish the last named operation so that the detachable heel may be withdrawn from the shoe it is unnecessary 10 to use any special tool, for any relative slender instrument such as a nail may be inserted in the opening 11 and between the spring tongue 19 and the guide and rest 14, which will force the spring tongue downward and disengage it from the arms 13.

Of course I do not wish to be limited to the exact details of construction as herein shown, as these may be varied within the limits of the appended claims without departing from the spirit of my invention.

Having thus fully described my invention, what I claim as new and useful, is:—

1. In combination with a fixed heel, a clamp comprising a cupped up body, a flange 25 projecting from the side walls of the body, an extension projecting from the front end of the roof of the body, said extension having an opening therein, a partition projecting from the roof into the interior of the body, arms formed from said partition, a guide and rest formed from the partition intermediate the arms and inclined toward the front edge of the roof, a detachable and interchangeable heel provided with a cavity 30 open at the front end and having a recess radiating therefrom, said recess arranged to receive the flange of the clamp and means situated within the cavity of the detachable heel for locking the latter upon the fixed 35 heel.

2. In combination with a fixed heel, a clamp comprising a cupped up body, a flange projecting from the side walls of the body, an extension projecting from the front end 45 of the roof of the body, said extension having an opening therein, a partition projecting from the roof into the interior of the

body, arms formed from said partition, a guide and rest formed from the partition intermediate the arms and inclined toward the front edge of the roof, a detachable and interchangeable heel provided with a cavity 50 open at the front end and having a recess radiating from the base of said cavity, said recess arranged to register with the flange 55 of the clamp when the detachable heel is drawn forward, and a locking plate situated within the cavity and projecting into the recess provided with means for engagement with the arms of the clamp to hold the detachable heel in position.

3. In combination with a fixed heel, a clamp comprising a cupped up body, a flange projecting from the side walls of the body, an extension projecting from the front end 60 of the roof of the body, said extension having an opening therein, a partition projecting from the roof into the interior of the body, arms formed from said partition, a guide and rest formed from the partition 65 intermediate the arms and inclined toward the front edge of the roof, a detachable heel provided with a cavity open at the front end and having a recess radiating from the base of said cavity, said recess arranged 70 to register with the flange of the clamp when the detachable heel is drawn forward, and a locking plate carried by the detachable heel situated within the cavity and projecting into the recess, said locking plate comprising a body, a pair of parallel arms, a bowed spring tongue having slots therein and prongs, said slots in the bowed spring tongue adapted to register with the arms of the clamp for locking the detachable heel 75 upon the fixed heel.

In testimony whereof I have hereunto affixed my signature in the presence of two subscribing witnesses.

HARRY W. CRANE.
